[57] CLAIM

The ornamental design for a mug, as shown and described.

DESCRIPTION

FIG. 1 is a top plan view of a mug showing my new design;

FIG. 2 is a side elevational view thereof looking from the left of FIG. 1;

FIG. 3 is a front elevational view thereof;

FIG. 4 is a side elevational view thereof looking from the right of FIG. 3.

FIG. 5 is a bottom plan view thereof.

The rear elevational view, not shown, of the mug is a mirror image of the front elevational view.
